UNITED STATES PATENT OFFICE.

WILLIAM W. HOPKINS, OF ST. LOUIS, MISSOURI, ASSIGNOR TO MOON-HOPKINS BILLING MACHINE COMPANY, OF ST. LOUIS, MISSOURI, A CORPORATION OF MICHIGAN.

CALCULATING-MACHINE.

1,032,678.

Specification of Letters Patent. Patented July 16, 1912.

Application filed March 7, 1907. Serial No. 361,075.

To all whom it may concern:

Be it known that I, WILLIAM W. HOPKINS, a citizen of the United States, residing at St. Louis, Missouri, have invented a certain new and useful Improvement in Calculating-Machines, of which the following is a full, clear, and exact description, such as will enable others skilled in the art to which it appertains to make and use the same, reference being had to the accompanying drawings, forming part of this specification, in which—

Figure 1 is a vertical longitudinal sectional view through a calculating machine illustrating my improvement; Fig. 2 is a view illustrating my improvement in an adjusted position; Fig. 3 is a similar view illustrating my improvement in a different adjusted position; and Fig. 4 is a top plan view of the printing type and associate parts.

This invention relates to a new and useful improvement in calculating machines and particularly to the means for operating the printing type from the actuating devices of the registering mechanism. The registering mechanism of the calculating machine shown in the accompanying drawings is similar to that illustrated and described in an application filed by Hubert Hopkins April 9, 1906, Serial No. 310,739.

The object of my present invention is to combine a suitable and appropriate registering mechanism with printing devices which are positioned by the register-actuators, said printing devices being in the form of segments or bars having solid type on their peripheries. These printing segments are independently adjustable and coöperate with mechanism whereby they are initially and independently released when positioned, and collectively released after being positioned so that the positioned bars will bodily make a printing impression.

With these objects in view, the invention consists in the construction, arrangement and combination of the several parts, all as will be hereinafter described, and afterward pointed out in the claims.

In the drawings, 1 indicates the side frames of the registering section of a calculating machine, in which side frames are mounted appropriate devices for coöperating with the registers.

119 indicates one set of register wheels,

and 268 another set of register wheels. These register wheels separately coöperate with appropriate carrying mechanism.

100 are the actuating racks for the registering wheels, which racks have slot and 60 pin connection with levers 102.

93 are stop pins for arresting the racks by coöoperating with shoulders 101 thereof in predetermined positions. These stop pins are positioned by setting pins 63 arranged 65 in a traveling carriage 57, which setting pins and traveling carriage are under the control of digit keys.

When an example has been set up in the setting pins of the traveling carriage the 70 operation of the power shaft, not shown, will cause the carriage and the setting pins to be bodily lifted so as to position the stop pins 93, after which the restoring bar 104 moves forward and permits springs 103 75 to impel levers 102 and their connected racks 100 forwardly until the shoulders 101 are engaged by the raised stop pins 93. The register wheels 119 or 268 are then 80 engaged with the racks, so that when the bar 104 restores the racks the item introduced into the machine by the keys will be registered in said wheels. In taking a total 85 of the wheels 119 or 268 are first engaged with the racks 100 before the racks are moved forwardly. The register wheels 268 are principally identified with the multiplying devices located at the rear of the machine, but with regard to these multiplying devices 90 no detailed description is here given because such is deemed unnecessary.

The forward ends of the racks 100 are each provided with a downward extension 101^a which coöperates with the printing segment to position the same.

2 is a comb plate secured to one of the cross frame bars of the calculating machine, and whose teeth project forwardly and are slotted so as to provide guide ways for lateral projections on the rear ends of links 3. The extensions 101^a of the rack bars project down between the teeth of the comb and in front of the lateral projections on the links 3. The end of each of these links 3 is connected to a printing segment 4, which printing segment is mounted in a lever 5 arranged on a stationary fulcrum 6. A spring 7 coöperates with the lower end of the printing segment 4, and tends to move the upper 105 end of said printing segment forwardly. 110

Whenever the rack bar 100 and its extension 101^a move forwardly, the printing segment controlled by said extension will be permitted to move forwardly and be positioned so as to have the printing type corresponding to the position of the rack bar in printing line. Thus the rack bar 100 may move forwardly and be arrested in one of ten different positions, the first position representing "0," the second "1," the third "2," and so on up to "9."

When the rack bar moves forward a pawl 8 whose upper end co-operates with the extension 101^a is permitted to rock so as to move its lower hooked end from under the rearward extension of lever 5. This pawl 8 being directly controlled by the rack bar extension, thus initially releases the lever 5 so that the operation of pawl 8 is a condition precedent to making a printing impression from the type segment associated therewith. If the rack bar 100 is not moved to zero position or to a position indicating a digit, the pawl 8 is not operated, and consequently the lever 5 controlled by said pawl cannot be operated. There is a pawl 8 for each lever 5, and each pawl has a spring 9 connected thereto which tends to move the pawl against a stop 10 when in its released position. The extension 101^a, by engaging the upper end of pawl 8, moves its hooked lower end under the lower end of lever 5.

11 indicates a rock shaft having a rock arm 12 connected by a link 13 to a rock arm 14 mounted on a shaft 15. Whenever the power shaft of the calculating machine is operated, except in the operations of multiplication, the shafts 15 and 11 are rocked.

16 indicates rock arms on the shaft 11, said rock arms carrying a bar 17 which operates under the rear ends of lever 5, said bar tending to restore the levers 5 to normal position after operation.

19 is a shaft on which are mounted pawls 20, the rear ends of said pawls being located under the bar 17. The forward ends of pawls 20 are in the form of hooks which co-operate with lateral extensions 5^a on the levers 5. Springs 21 tend to hold the pawls 20 in such position that they will engage the lateral extensions 5^a and hold the levers 5 against movement.

Means must be provided to drive the type segments against the paper on the platen, and this means is shown in the accompanying drawings as consisting of arms 22 loosely mounted on the shaft 11, each of said arms being provided with a roller or lateral projection 23 engaging the rearward extension of lever 5. Springs 24 are connected to the arms 22 and tend to pull them downwardly. It is obvious that these springs 24 could be directly connected to the rear ends of levers 5, but I prefer to employ the arms 22 with the rollers 23 because by so doing the con-

tractive movement of the springs 24 is considerably lessened.

25 is a bar secured in some suitable manner to the framing of the machine, whose under side is preferably faced with leather 26 or other suitable buffer material. In operation the forward ends of levers 5 strike against this bar and are arrested. The type segments are appropriately mounted in the forward ends of levers 5 by slot and pin connection, so that when the levers 5 strike the buffer 26 the type segments may move upwardly by momentum and deliver an impacting blow against the paper on the platen. The spring 7 tends to draw the type segments down to normal position after the printing impression has been made.

27 is a platen which is preferably mounted in a laterally movable carriage, not shown, which is operated by appropriate paper-feeding devices, not shown.

28 indicates a sheet of paper supported by the platen.

There are as many type segments as there are normally active racks in the calculating machine and each type segment is initially positioned by its spring 7 whenever a rack 100 moves forward. As before stated, the forward movement of the rack releases its related pawl 8 so that the lever 5 carrying the type segment identified with the particular rack operated is initially released. When the power shaft of the machine is operated the rod 17 is depressed and will operate all the pawls 20, releasing all of the levers 5 from restraint of these pawls. Such of the levers 5 as have been initially released by the pawl 8 are thus free to move, and the springs 24 now come into action and collectively raise all of the positioned printing segments until said segments are arrested by the stop bar 25 and its cushioning device. Momentum imparted to the printing segments, however, causes them to continue their upward movement and deliver an impacting, type-impressing blow on the paper carried by the platen. After making the printing impression the bar 17 is restored to normal position and coincidentally therewith the racks 100 are likewise restored.

The restoration of bar 17 raises the rear end of all of the operated levers 5 and again places the springs 24 under tension, and by releasing the pawls 20 all of said pawls again become engaged with the projections 5^a of their respective levers 5. The restoration of the racks 100 causes the pawls 8 to become engaged with the rear ends of levers 5, and when the parts are in such position, as shown in Fig. 1, the machine is in readiness for operation. In Fig. 2 the parts are shown in printing position, wherein zero is being printed, while in Fig. 3 the parts are shown as being in a position they assume in printing "9."

It will be noted from the above that the racks 100 are not connected with the type segments so as to positively move the type segments forwardly. In the calculating machine illustrated in the application of Hubert Hopkins before referred to, in operations of multiplication, the racks 100 are operated, but means are provided for preventing the vibration of the bar 17. Thus during certain portions of multiplying operations the racks are operated, but the printing mechanism is not operated, and consequently no printed record is made of these operations. In the construction illustrated in the accompanying drawings it will be observed that if the bar 17 is not operated the racks 100 are free to move forwardly without operating the printing segments, and thus no printed record will result from such movement of the racks.

While I have illustrated type segments and referred to type segments throughout this description, it is obvious that the printing type could be arranged on wheels in a manner well understood in this art, in which event, in order to impart proper movement to such type wheels, each wheel would have a pinion conjoined thereto, which pinion would mesh with a rack connected to or forming part of the rack 100. It is also obvious that instead of having type in the form of a segment said type could be mounted on a bar directly connected to the racks 100.

I am aware that heretofore it has been the common practice to connect directly with or operate from the actuating devices of the register, type-carrying members in which are mounted loose type, these loose type in printing line being struck by type hammers so as to make a printing impression. These loose type, of necessity, require individual springs and special mountings, and these multiply the number of parts entering into the construction of such a printing mechanism. In my construction the type arranged on the periphery of a wheel, on a segment or on a bar, are all solid and connected together, and one type of a series is not movable independently of another type in the same series. This materially reduces the cost of manufacture and renders the construction less liable to get out of order. Therefore, in the following claims, in order to distinguish from the type carriers with their loosely mounted type, I shall refer to the kind of type which I employ as "rigidly mounted type."

Having thus described the invention, what is claimed as new and desired to be secured by Letters Patent is:

1. In a calculating machine, registering wheels, actuating devices therefor, printing type and yielding means for moving said type in one direction upon the movement of

its associated actuating device, said type being positively moved in the opposite direction by the said actuating devices.

2. In a calculating machine, registering wheels, actuating devices therefor, printing type, and a connection between said type and said actuating devices whereby the actuating devices may operate independently of the said type.

3. In a calculating machine, registering wheels, actuating devices therefor, printing type, means for moving said type and means for restraining the movement of said type when said actuating devices are moved.

4. In a calculating machine, the combination with registering wheels, actuating devices therefor, rigidly mounted printing type, a connection between said actuating devices and said type whereby the actuating devices may move independently of said type, yielding means for holding said type in connection with said actuating devices to partake of the movements thereof, means for restraining the movements of said type during the movement of said actuating devices, pawls controlled by said actuating devices for initially releasing said type, and pawls also coöperating with said type, said last mentioned pawls being controlled by said restraining means.

5. In a calculating machine, a register, actuating devices therefor, printing type whose position is controlled by said actuating devices, a lever on which said printing type are pivotally mounted, and two restraining pawls coöperating with said lever, one of said restraining pawls being controlled by said actuating devices, and means for operating the other of said restraining pawls; substantially as described.

6. In a calculating machine, a register, an actuating rack therefor, printing type, a link connection between said rack and said printing type, a lever in which said type are pivotally mounted, two restraining pawls for said lever, one of said restraining pawls being operated by said racks, restoring means for said printing type, said restoring means operating the other of said restraining pawls, springs for moving said lever when said last mentioned pawl is operated, and a stop bar with which said lever coöperates; substantially as described.

7. In a calculating machine, a register, actuating devices therefor, said actuating devices having extensions, a comb plate between the teeth of which said extensions project, pivotally mounted type, and links connected to said type and movable in one direction only by said actuating devices: substantially as described.

8. In a calculating machine, the combination with register-actuating devices, of pivotally mounted type whose position is yielding controlled by said register-actuating

devices when moving in one direction, a lever having slot and pin connection with said pivotally mounted type, means for controlling said lever, a stop bar against which 5 said lever strikes, and a platen carrying a sheet of paper for receiving an impacting blow from said type; substantially as described.

9. A calculating machine, printing type, 10 means for positioning said printing type, a lever carrying said type, and yielding means for operating said lever, said means comprising a loosely pivoted arm having a lateral projection or roller engaging said lever, 15 and a spring connected to said arm; substantially as described.

10. In a calculating machine, a register-

actuating device, type which are positioned by said register-actuating device, a lever with which said type have a slot and pin 20 connection, a stop bar for arresting the movement of said lever, and for causing said type to deliver an impacting blow, a platen for supporting a sheet of paper, and restraining pawls coöperating with said lever; 25 substantially as described.

In testimony whereof I hereunto affix my signature in the presence of two witnesses, this fifth day of March 1907.

WILLIAM W. HOPKINS.

Correction in Letters Patent No. 1,032,678.

It is hereby certified that the name of the State of incorporation of the assignee in Letters Patent No. 1,032,678, granted July 16, 1912, upon the application of William W. Hopkins, of St. Louis, Missouri, for an improvement in "Calculating-Machines," was erroneously written and printed "Michigan," whereas said State should have been written and printed *Missouri*; and that the said Letters Patent should be read with this correction therein that the same may conform to the record of the case in the Patent Office.

Signed and sealed this 13th day of August, A. D., 1912.

[SEAL.]

E. B. MOORE,

Commissioner of Patents.
